INCORPORATED, OF NEW YORK, N. Y., A CORPORATION OF NEW YORK.

TELEPHONE SYSTEM.

1,271,337.

Specification of Letters Patent.

Patented July 2, 1918.

Application filed December 30, 1916. Serial No. 139,935.

To all whom it may concern:

Be it known that I, ALBEN E. LUNDELL, a citizen of the United States, residing at New York, in the county of Bronx and 6 State of New York, have invented certain new and useful Improvements in Telephone Systems, of which the following is a full, clear, concise, and exact description.

This invention relates to telephone systems, and particularly to systems of the type in which switching apparatus at the central telephone office operates automatically to find and extend the lines of calling subscribers. The invention is especially directed toward the provision of an improved organization for preventing the connection of a line finding switch with two lines simultaneously and for permitting the rapid assignment of line finding switches to 20 lines calling simultaneously or in rapid succession, but preventing the starting of two or more line finding switches by a single calling line.

This application is in part a continuation 25 of a prior application by the same applicant, Serial No. 16,357, filed March 23, 1915, and is related with respect to the disclosure of the means for preselecting a plurality of connecting circuits, to Patent No. 1,166,466, 30 issued January 4, 1916, to the applicant herein.

In the embodiment of the invention disclosed herein, the lines are divided into groups and are multiply connected with 35 corresponding groups of stationary terminals on a plurality of line finder switches, each of the finder switches having a set of brushes for each of the groups of stationary terminals. The selection of a calling line 40 is effected by first causing the tripping of the set of finder switch brushes corresponding with the particular group in which the calling line is located, and then causing the brushes to move to and stop upon the terminals of the particular line that is calling. If two sets of brushes upon the finder switch should be tripped, the finder circuit 45 would be connected with two correspondingly located lines in different groups, and 50 the prevention of such action is one of the objects of this invention.

In this system a plurality of finder switches are provided for taking the calls as they are initiated, each finder switch in 55 starting placing another finder switch in

readiness to be started. The calling condition of a line which causes the starting and group selecting operation of a finder switch may persist for some time after the next finder switch is placed in readiness to be 60 started. This invention provides an improved organization in which a calling line after it has started a finder switch, is deprived of control over the starting and group selecting mechanism until the calling 65 line is found and its starting condition altered, thus making it impossible for a single call to start and control more than one finder switch.

As the calls may, in heavy traffic periods, 70 follow each other in rapid succession, it is desirable to provide an organization in which when one finder switch has been started in search of a calling line a second switch may be placed under control of the 75 starting circuit with the minimum of delay. This is accomplished, in the system of this invention, by holding one finder switch in a waiting position in operative relation with the starting circuit, another finder 80 switch in an allotted position ready to move into the waiting position when the waiting finder switch takes a call, and providing an electrically controlled allotting switch for finding idle finder switches and closing 85 circuits to move them one at a time into the allotted position as the finder switch in that position is moved out. Thus two—or, by a further application of the principle of this invention, more than two—finder 90 switches are held in a preselected position, so that when two, or more, calls are initiated practically simultaneously or in rapid succession a minimum of delay is necessitated in the automatic assignment of finder 95 switches for taking calls.

A specific embodiment of the invention in which the above-mentioned and other advantageous features are realized is illustrated in the accompanying drawings in 100 which Figures 1, 2, and 3, taken together, and with Fig. 1 at the left and Fig. 3 at the right of Fig. 2, represent as much of a complete system as is necessary to disclose the organization and mode of operation of 105 the novel features of the invention.

Referring to the organization illustrated in the drawing, A indicates one of a group of substations, the lines of which terminate in the section of the panel bank traversed 110

by the uppermost set of brushes of each of the line finder switches. B represents one of a group of substations the lines of which terminate on another section of the panel bank. A third group of lines terminating upon still another section of the panel is indicated by the two group relays at the bottom of Fig. 1.

The start relay 18 (Fig. 1), is common to all of the groups of lines terminating in the several sections of the panel bank of a group of finder switches. A group cut-off relay 19 and a group lockout relay 20 are provided for each group of lines terminating on a particular section of the panel board. 21 is the usual line relay and 22 is the usual cut-off relay for each line. The wires or conductors extending from the windings of the relays 19, 19', etc., are multiplied to the back and front contacts, respectively, of the inner armature of all the line relays in their respective group of lines. The conductor terminating at the back contact of each of the relays 19, 19', etc., is similarly multiplied to the front contacts of the outer armatures of all the line relays of the associated group. A conductor extends from the winding of the common start relay 18 serially through normally closed contacts in the lockout relays 20, 20', etc., of the different groups, and the right-hand resting contacts of these lockout relays have multiple connection with a conductor 24 that is controlled in resting contacts of the common start relay 18.

35 The line finder switch mechanism to the stationary terminals or contacts of which the subscriber's line circuits are connected, is illustrated diagrammatically in Fig. 2 as comprising two finder switches, the first and last in the group or series of switches that serve the groups of lines indicated. The finder switches may be substantially like the switch illustrated and described in the patent to James L. McQuarrie, No. 1,177,044, issued March 28, 1916.

To the upper end of each switch shaft is attached a brush arm, the brushes 35 and 73 of which coöperate with the corresponding commutator segments 34 and 44 as the shaft moves up or down. The upward and downward movement of the brush carrying shaft of each finder switch is controlled by the up-drive magnet 5 and the down-drive magnet 45, which serve to thrust the extension 50 2 against one or the other of the oppositely rotating power members 3. The four contact terminals of each line for each finder switch are arranged side by side in the same horizontal line, but are shown in an inclined 55 relation for clearness of illustration.

For each section of the panel bank there is provided a tripping device, common to all of the groups of finder switches, that includes a trip magnet 17 which when it is 60 energized attracts its armature 16 and ro-

tates a common trip rod 11. Upon this common trip rod are carried a number of tripping yokes 12, one for each of the sets of brushes of the finder switch group. When the trip rod is rotated, all of the yokes 12 are brought into position to engage the corresponding trip levers 9 on all of the finder switches, and whichever of the finder switches is started at this time has its set of brushes tripped that corresponds with this particular section of the panel bank. The brushes are normally held away from the line terminals they traverse by an insulating member carried upon the arm 8; and when the tripping lever 9 is engaged by the tripping yoke and tilted, this insulating member is withdrawn and the brushes are permitted to move toward each other so as to come into engagement with the corresponding line terminals as the switch 85 moves up.

The finder circuits F' and F³, of which the line finders shown in Fig. 2 are the terminals, are illustrated in Fig. 3; and at the bottom of the figure are shown certain relays 90 and switches which govern the assigning or allotting of the different finder circuits to the subscribers' lines as they call. As this invention is not concerned with the particular manner in which the connection of a calling line shall be extended beyond the finder circuit to a called line, such extension circuits and apparatus are not illustrated. The extension of the connection beyond the finder circuit may be by means of plugs and jacks, by means of automatic switches, controlled by an operator or directly by the calling subscriber, or in any other convenient and well-known way. The sequence switches that are employed in the organization are 100 shown diagrammatically, and may be of the type disclosed in Patent No. 1,127,808, issued February 9, 1915, to Reynolds and Baldwin. The numerals applied to contacts 66 of finder sequence switches 28 and contacts 60 of al-105 lotter sequence switch 57 indicate the only positions of the respective sequence switches in which the associated contacts are open, the numerals applied to the other contacts of each of these switches indicate the only positions of the respective switch in which the associated contacts are closed. In the following description a numeral within parentheses indicates a position in which the sequence switch contact represented by the associated number is closed. It is believed that the further details of organization of the system will appear from the description 115 of operation of the system which follows.

When the subscriber at substation A removes the receiver from its hook, a circuit is completed from grounded battery through line relay 21, inner armature and back contact of cut-off relay 22, over the line, through the substation apparatus and back to ground 125 130

through the outer back contact and armature of relay 22. Relay 21 is energized and completes a path from battery, through the right-hand winding of group cut-off relay 19, the front contact and inner armature of relay 21, conductor 23, to the multiple test contacts of the line in its section of the panel bank. This identifies this particular line as a calling line to the line finder 10 brushes that thereafter engage the line terminals. The energization of relay 21 also completes a circuit from battery through the left-hand armature and back contact of start relay 18, right-hand normal contact of 15 lockout relay 20, winding of said relay, back contact of relay 19, outer front contact and armature of relay 21 to ground. Relay 20 pulls up and completes a holding circuit for itself in series with relay 18, as follows: 20 from battery through relay 18, left-hand front contact and armature of relay 20, winding of said relay, armature and back contact of relay 19, an outer front contact and armature of relay 21, to ground. Relay 25 25 is energized, thus opening the initial energizing circuit by removing battery from the common wire 24, so that if a subscriber in some other group, as the group containing station H, calls at this instant, no battery 30 will be supplied to the lockout relay 20 of that group, and consequently no operation will result from initiating a call until the common relay 18 is released.

The energization of relay 20 completes a 35 circuit in parallel with its own winding, this circuit extending by way of the front contact and right-hand armature of relay 20, and to ground through the trip magnet 17 of the corresponding group. Magnet 17 is 40 energized and rotates the trip rod 11 so as to place the associated yokes 12 in the path of the trip levers 9 of the corresponding brushes of such of the switches as are in normal position.

45 For reasons that will hereinafter be set forth, only one of the finder circuits having access to the groups of lines in which the calling line is located, has its sequence switch in position to be responsive to the closure 50 of the start circuit by the energization of the relay 18. When relay 18 is energized, it completes a circuit from battery, through relay 25 of the finder circuit that is in readiness, sequence switch contact 26 (1), start 55 wire 27, front contact and armature of relay 18 to ground. Relay 25 is energized and completes a circuit from battery through sequence switch motor magnet 28, sequence switch contact 46 (1), sequence switch contact 38 (1), front contact and left-hand armature of relay 25 to ground. The finder 60 sequence switch thereupon goes into position 2.

In position 2 a circuit is completed from 65 battery, through the up-drive clutch magnet

5 (see Fig. 2), conductor 31, sequence switch contact 29 (2), front contact and left-hand armature of relay 25 to ground, whereupon the preselected finder switch is moved upward. As it leaves its normal position, the 70 set of brushes adapted to traverse the section of the panel in which the calling line terminates, is released by means of the associated yoke 12 being in engagement with the trip lever 9 of that set of brushes. 75

In position 2 of the finder sequence switch, a holding circuit for relay 25 exists from battery, through the winding of said relay, front contact and right-hand armature thereof, sequence switch contact 37 (1 to 2-1/2), 80 lower sequence switch contact 32 (1 to 3), resistance 67, conductor 33, interrupting segment 34 and interrupter brush 35 of the line finder commutator (see Fig. 2) to ground. This circuit maintains the locking circuit of 85 the relay 25, except when the brush 35 is in engagement with an insulating segment on the interrupter 34, which occurs only when the brushes of the switch are centrally positioned on a set of contacts in the terminal 90 bank. A branch from the above-traced holding circuit also extends from upper sequence switch contact 32 (1 to 3) to the test brush 36 which is adapted to traverse the test contacts associated with the test conductor 23. 95 The test conductors 23 of all non-seeking lines of the calling line group are connected to ground through the back contacts of their respective line relays 21 and the left-hand winding of relay 19. Thus relay 19 will be 100 energized when the brush 36 engages the first test terminal connected to a non-seeking line, and will remain energized as long as the switch is passing over non-seeking lines, 105 the test brush and the test terminals consecutively engaged by it being so related that the brush engages one test contact before it disengages another. Relay 19 of the group in which the calling line is located, in pulling up, breaks the holding circuit for 110 relay 20. Relay 20 in turn opens the circuit of start relay 18 and trip magnet 17, thus returning the circuits to a condition such that a call in a different group of lines will be immediately answered. But as relay 19 115 of the calling line group is kept energized to disconnect the associated relay 20 from the line relay contacts of the corresponding group until the seeking line is found, the lines of this particular group during this interval have no control over the group tripping magnet 17 and the starting relay 18. Thus the calling lines of some other group have the preference over calling lines that may be waiting in the group that first called. 120 125

The relay 25 of the finder circuit and the relay 19 of the group circuit are maintained energized through the test brush 36 until the brushes of the switch are centrally positioned on the contacts of the line which has 130

initiated the call, when a circuit will extend from battery, through the right-hand winding of relay 19, front contact and inner armature of line relay 21 of the calling line, 5 test conductor 23, brush 36, sequence switch contact 32 (1 to 3), sequence switch contact 37 (1 to 2-1/2), right-hand armature and front contact of relay 25, and the winding of that relay, to the same pole of the battery. 10 As relays 19 and 25 are thus in a loop circuit that does not include a source of current, both are deenergized. Relay 25 falls back quickly, and in doing so not only opens at its left-hand front contact the circuit of the up-drive magnet 5, but also at its right-hand front contact opens the locking circuit for itself which up to that instant had been maintained alternately by way of the grounded test conductors of the non-calling lines over which the test brush 36 had been passing, and the commutator strip 34 and brush 35 of the line finder. 15 Relay 25 releases quickly; but the group cut-off relay 19 is made slow to release its armature, as by providing its core with a copper sleeve, and before the armature is released so as to close the circuit from the ground at the line relay 21 of the calling line to the group relay 20, relay 25 of the finder circuit has fallen back and applied ground to the brush 36 and test conductor 23 by way of sequence switch contact 47 (2 to 2-1/2). Group cut-off relay 19 is thus held energized until its circuit is broken by the falling back of the armature of line relay 21. 20 This is effected a moment later as follows: Relay 25 in falling back completes a circuit that extends from battery through sequence switch motor magnet 28, sequence switch contact 46 (2), sequence switch contact 38 (2), back contact and left-hand armature of relay 25 to ground. The sequence switch thereupon moves to position 3. In moving out of position 2 a circuit is completed from battery, through conductor 39, sequence switch contact 40 (2-1/2 to 10), brush 41, conductor 42, and cut-off relay 22 to ground. Relay 22 is energized and interrupts the circuit of line relay 21, which permits its armatures to fall back, thus removing the calling ground applied to the group circuit by way of its outer armature, and at the same time deenergizing group cut-off relay 19 by breaking the circuit of the right-hand winding of that relay. Thus after the calling line is found, the falling back of group relay 19 and closing of its normal contacts again gives the group in which the calling line is located access to its trip magnet, and to the start relay 18 and, through it, to the finder circuits which it controls. 25

The talking condition of the finder circuit is that which exists when the finder sequence switch is in position 13; and the motor magnet 28 of the sequence switch is

controlled to move the sequence switch through its various stages into this position by means of circuits which are not concerned with this invention, and which need not be described.

When the sequence switch reaches position 13, the talking circuit, which includes the usual repeating coil 48, answering supervisory relay 49 and calling supervisory relay 50, is completed by way of sequence switch contacts 51, 52 and 53 closed in this position. In position 13, sequence switch contacts 30 are also closed to apply battery through resistance 54 to the third conductor of the finder circuit, and thence to local conductor 42 of the line circuit, to hold the line cut-off relay 22 energized.

As long as the calling subscriber is at his telephone, the answering supervisory relay 49 remains energized and holds relay 25 energized over a circuit that extends from the winding of relay 25 to ground by way of the contacts of the relay 49 and sequence switch contacts 55 (13). When the calling subscriber replaces his telephone, the falling back of relay 49 opens this circuit and permits the deenergization of relay 25. The left-hand armature of relay 25, in falling back, applies a ground for moving the finder sequence switch out of position 13 by way of a circuit which includes the motor magnet 28 of the sequence switch, and sequence switch contacts 46 (13) and 38 (13).

The finder sequence switch thereupon moves to position 15 in which it closes a circuit for the return of the finder switch, this circuit extending from battery through down-drive magnet 45 of the finder switch, sequence switch contacts 38 (15) and the back contact and left-hand armature of relay 25 to ground. In the last stage of the downward movement of the finder switch, brush 73 grounds segment 74 of the line finder commutator. This moves the finder sequence switch out of position 15 and to position 16 by means of a circuit that includes the motor magnet 28 of the sequence switch, sequence switch contacts 56 (15), segment 74 and brush 73 of the line finder commutator to ground.

The further movement of the finder sequence switch back to its 1 or normal position is governed by circuits and apparatus that have to do with the assigning or allotting of non-busy finder circuits to the various calling lines as they initiate their calls. The assigning or allotting of the finder circuits is controlled by a sequence switch 57 and relays 58 and 59 common to all of the finder circuits and switches of the group. In the specific embodiment of the invention, illustrated, the two finder circuits F^1 and F^3 that are shown are assumed to be the first and last of the series or group of such circuits; and the switch contacts of the allotting

130

sequence switch 57 are illustrated as being adapted to control the allotting of three such finder circuits, the two circuits that are shown, and an intermediate circuit that is not shown. The allotting sequence switch 57, as indicated on the drawing, has its contacts 60 so arranged as to hold the motor magnet circuit of the switch closed excepting in positions 1, 6 and 12 of the switch, while the 10 contacts 61 are adapted to be closed in these three positions.

If it be assumed that the allotting sequence switch 57 is moved out of position 12, in a manner which will be described hereinafter, 15 it will rotate until it comes to position 1 where the circuit of the motor magnet will be opened in sequence switch contacts 60. When the allotting sequence switch moves to 20 position 1 contacts 61 of this switch close a circuit from ground to contacts 62 of the sequence switch of finder circuit F^1 . If, when this occurs, finder circuit F^1 is busy or is awaiting a call, its sequence switch contacts 62 will be in some one of the 25 positions from 1 to 15, and consequently a circuit for continuing the movement of the allotting sequence switch 57 will be completed from battery through the motor magnet of the allotting sequence switch, sequence 30 switch contacts 62 (1 to 15) of finder circuit F^1 , contacts 61 (1) of allotting sequence switch 57 to ground.

But if the finder circuit F^1 has been freed, in the manner described above in tracing the 35 establishment and disestablishment of a connection, and is available for use, its sequence switch will be in position 16 and lower contact 62 (1 to 15) will be open. This being the case, when the allotting sequence switch 40 57 has moved to its position 1, corresponding with this finder circuit, it comes to rest, as the circuit of its motor magnet is interrupted at lower sequence switch contacts 62 of finder circuit F^1 .

45 But as sequence switch contacts 62 of the line finder F^1 are in position 16, a circuit for moving sequence switch 28 of finder circuit F^1 is completed from battery by way of the motor magnet, sequence switch contact 50 62 (16), allotting sequence switch contact 61 (1) to ground. This causes the sequence switch of finder circuit F^1 to move to position 18, in which position the sequence switch of the finder circuit thus allotted is 55 placed under the control of the relays 58 and 59 common to the group of finder circuits. The movement of the sequence switch of 60 finder circuit F^1 to position 18 leaves the allotting sequence switch 57 still in position 1, as the circuit of the motor magnet of the allotting sequence switch still remains open in sequence switch contacts 62 of the finder switch F^1 .

The sequence switch of the allotted finder 65 circuit F^1 remains in position 18 until an-

other one of the finder circuits which has been waiting in normal position 1 of the finder sequence switch is appropriated by a calling line. Assuming that the waiting 70 finder circuit is circuit F^8 , when the initiation of the call causes the energization of relay 25 of F^8 and the movement of the associated sequence switch out of position 1 and into position 2, as previously described, the closure of sequence switch contact 72 of 75 the finder circuit F^8 and the starting of the associated finder switch completes a circuit for the energization of the common relay 80 58 that extends from battery, through the winding of relay 58, by way of conductor 63, sequence switch contact 72, (2) of finder circuit F^8 to commutator segment 44 of the associated finder switch, and thence to ground when the associated grounded brush 43 engages the segment in the upward movement of the brush shaft. Relay 58 attracts its armatures, closing a holding circuit for itself to ground by way of its left-hand armature and the right-hand resting contacts of relay 59, and completing in its right-hand contacts a circuit for the energization of relay 59 by way of conductor 64 and sequence switch contacts 46 (18) and 38 (18) of finder circuit F^1 , the sequence switch of which was moved into position 18 by the 85 allotting sequence switch 57 in the manner already described. Relay 59 in operating 90 closes a holding circuit for itself in its left-hand contacts by way of conductor 64 and the path just traced, and in its right-hand contacts opens the locking circuit of relay 58 and applies ground by way of conductor 65 and sequence switch contacts 56 (18) of finder circuit F^1 to the sequence switch motor magnet of that finder circuit. This causes 100 the sequence switch of finder circuit F^1 to move out of position 18 and into position 1, 105 where it waits in readiness to start its associated finder switch in response to the next call received.

In moving out of position 18, the locking circuit of relay 59 is opened in sequence switch contacts 46, thus restoring relay 59 to 110 its normal condition. Also in moving into position 1, the sequence switch of finder 115 circuits F^1 closes in contacts 62 an energizing circuit for the motor magnet of the allotting sequence switch 57 to ground by way of contact 61 (1) of the allotting sequence switch, which causes that switch to move 120 out of position 1 and continue its movement until it finds another finder circuit that has been freed and is standing with its sequence switch in position 16, where the allotting operation as already described, is repeated. Thus each preselected finder circuit, as it is 125 appropriated by a calling line, causes a previously allotted finder circuit to be placed in readiness to take the next call that gains access to the starting circuit, and causes the 130

- operation of the allotting sequence switch to allot another finder circuit that shall be next in order when the finder circuit held in readiness shall have been taken.
- 5 The manner in which the organization operates to prevent two or more sets of brushes of a single finder switch being tripped by simultaneously existing calls in different groups, with the consequent connection of the finder circuit with correspondingly located lines in different groups, is as follows: The group relay 20, 20', etc., of a group, which is under the control of any line of that group, and which in turn controls the corresponding group tripping device, has an energizing circuit for starting its operation and an energizing circuit for continuing or maintaining its operation. The initial energizing circuit for each of the group relays is opened in contacts of that relay when the relay is operated, and the initial energizing circuits for all of the group relays are opened when the common start relay 18 is operated. The maintaining or continuing energizing circuit is closed with respect to any group relay when that relay is operated, and at the same time is interrupted with respect to any group relay beyond it in the series. The closure of the maintaining energizing circuit by the operation of any of the group relays is accompanied by the opening of the initial energizing circuit for all of the relays by the actuation of the common relay 18, whose winding is included in the continuing energizing path. Therefore, each group relay in operating acts to cut off the maintaining energizing circuit for all the group relays beyond it in the series, and also acts through the medium of the common relay 18 included in the maintaining circuit, to deprive all of the group relays of the series of an initial energizing circuit, and, therefore, to guard against some other group relay ahead of it in the series being operated, by a call initiated a moment later, to deenergize the first operated group relay.
- To illustrate, it may be assumed that station A in the first group and station B in the second group call simultaneously. The initial energizing circuits for both of the corresponding group relays 20 and 20' being closed in the resting contacts of the common relay 18 and in the right-hand resting contacts of each group relay, the relays 20 and 20' are energized and start to attract their armatures. In attracting their armatures, each group relay interrupts its initial energizing circuit in the right-hand resting contacts of the relay, and thereafter the energization of each relay is dependent upon the continuing energizing path that includes the winding of the common relay 18 and is adapted to be closed in the left-hand contacts of the group relay. But the relay 20,

in closing the continuing energizing path by way of its left-hand front contacts, opens that path to the relay 20' of the next group in the series and to the relays of the groups beyond. Therefore, only the group relay of 70 the substation A group is operated to energize the associated group tripping magnet. Relay 20' of the second group, being deprived of a continuing energizing circuit, falls back and closes its resting contacts. 75 But, in the meanwhile, the common relay 18, being included in the continuing energizing circuit that was closed by group relay 20, is operated to interrupt in its left-hand resting contacts the initial energizing circuit for all the groups. Therefore, as long as the group relay 20 remains actuated to cause the tripping of the corresponding brushes of the finder switch, no other group relay can be operated to trip its corresponding switch brushes. As soon, however, as the switch searching for the line of substation A in the first group reaches the first terminals in the bank, relays 20 and 18 are released to give the other groups control 80 over the starting and tripping circuits, and the selection of the line of substation B in the second group immediately takes place.

The arrangement of the system is such that although a second finder switch is 95 brought into operative relation with the starting circuit early in the movement of the started finder switch and before that switch has found the calling line and changed its calling condition, the second finder switch is 100 not started by this calling line. This result is accomplished by automatically making the calling line ineffective to control the starting and group tripping circuits immediately 105 after the started finder switch has passed its group selecting stage, and keeping the calling line ineffective to control these circuits until after the started finder switch has found the line and altered its calling condition. Thus, after the started finder 110 switch has passed through the group selecting stage of its movement, it closes a circuit by way of the commutator segment 44 which moves the waiting or pre-selected finder circuit from position 18 to position 1 of its 115 sequence switch, thus placing this second finder circuit in condition to respond to a closure of the starting circuit. If at this time the calling line that started the first finder switch should continue to have control over the starting circuit, this second finder switch would be started also. But an instant before the second finder switch has been placed in operative relation with the starting circuit, the test brush 36 of the 120 started switch has closed a circuit by way of the test conductor of a non-calling line that operates the group cut-off relay 19 to release the associated relay 20 and open the starting circuit; and thereafter the relay 19 remains 125 130

energized to deprive the calling line, and all other lines of the group, of control over the relay 20 until the calling line has been found, as has hereinbefore been described. The 5 cutting off of all of the lines of the group from control over the starting and tripping circuit until the calling line has been found, also has the effect of giving calls in other groups control over the starting and tripping circuits during this interval in preference to calls waiting in the same group, thus preventing the monopolizing of the finder circuits by calls in a single group during heavy traffic periods.

15. What is claimed is:

1. In a telephone system, telephone lines, a finder switch, a starting circuit, means for energizing said starting circuit by any line in calling to start said switch to find 20 said line, an electromagnet for removing said starting circuit from the control of the calling line, and an energizing circuit for said magnet maintained through a brush of said switch and the terminals of non-calling 25 lines.

2. In a telephone system, a group of telephone lines, a finder switch, a starting circuit, means for energizing said starting circuit by any line in calling to start said switch to find said line, an electromagnet for preventing a second calling line in said group from energizing said circuit, and an energizing circuit for said magnet maintained through a brush of said switch and the terminals of non-calling 35 lines.

3. The combination with a plurality of lines, of a plurality of finder switches for making connection therewith, a starting circuit energized by any of said lines in calling, 40 means made active in the energization of said starting circuit for starting one of said switches, means made operative at the outset of movement of said switch for advancing said starting circuit to the next switch, an 45 electromagnet for preventing said calling line from starting said next switch, and an energizing circuit for said electromagnet closed by said switch in its passing engagement with the terminals of non-calling lines.

50. 4. The combination with a plurality of lines arranged in groups, of a plurality of finder switches adapted for group and individual line selection, a device for each group of lines for controlling the group selecting 55 operation of said finder switch, means controlled by any line of the corresponding group in calling for actuating said device, an electromagnet for rendering said group selecting device ineffective, and an energizing 60 circuit for said electromagnet completed in the passing engagement of a finder switch with the non-calling line terminals of the corresponding group.

65. 5. The combination with a plurality of telephone lines divided into groups, of a

relay associated with each group and responsive to the initiation of a call in that group, a group selecting mechanism selectively controlled in the operation of the various group relays, a relay common to all of 70 said groups, initial energizing circuits for all of said group relays controlled in normal contacts of said common relay, and an energizing circuit for said common relay closed in the operation of any of said group relays. 75

6. The combination with a plurality of telephone lines arranged in groups, a group relay associated with each group and operated by any of the lines of the corresponding group, a group selecting mechanism selectively controlled by said relays, a relay common to said groups, initial energizing circuits for said group relays controlled by said common relay, and an energizing circuit for said common relay controlled in the 85 operation of any of said group relays.

7. In a telephone system, the combination with a switch having a plurality of normally inactive brushes and a corresponding plurality of groups of stationary contacts 90 arranged to be traversed by said brushes respectively, telephone lines arranged in groups terminating in said groups of contacts, a tripping device for each set of brushes for rendering the same active, a 95 group relay for each group of telephone lines, said group relay being actuated by the initiation of a call in the corresponding group, an energizing circuit for the corresponding tripping device controlled by each 100 group relay, a common relay, means actuated in the operation of the same for preventing the operation of any unoperated one of said group relays, and means made active in the operation of any group relay 105 for operating said common relay.

8. In a telephone system, the combination with a finder switch having stationary terminals arranged in groups and normally inactive brushes corresponding with said 110 groups of terminals, of a tripping device for the brush of each group, telephone lines arranged in groups terminating in said groups of terminals, a group relay for each group of lines, said group relay being responsive to the initiation of a call in the corresponding group and controlling the operation of the corresponding tripping device, an initial energizing circuit for each of said group relays, a common relay adapted when operated to open said initial energizing circuits and cause the movement of said finder switch, and means responsive to the operation of any of said group relays for causing the actuation of said common relay. 115

9. In a telephone system, the combination with a plurality of telephone lines arranged in groups, of group selecting mechanism associated with each group of lines, a group relay for each group of lines having an ini- 120

tial energizing circuit closed by the initiation of a call in the corresponding group, means responsive to the operation of said group relay for actuating the corresponding group 5 selecting mechanism, a common relay controlling in its normal contacts the initial energizing circuits of said group relays, an energizing circuit for said common relay extending serially through normally closed 10 contacts of each of said group relays, and means actuated in the operation of any of said group relays for completing said last mentioned energizing circuit and disconnecting it from the succeeding group relays 15 of the series.

10. The combination with a plurality of lines arranged in groups, of a finder switch adapted for group and individual line selection, a relay for each group operated by any 20 line of the group in calling, means made active by each of said relays in operating for starting said finder switch and controlling its group selecting operation, a relay for each group acting when operated to de- 25 energize said first-mentioned group relay, a test conductor for each line closed as the finder switch comes into operative relation with the associated line, and an energizing circuit for said last-mentioned relay com- 30 pleted by way of the test conductors of the non-calling lines of the group.

11. The combination with a plurality of lines, of a plurality of finder switches for making connection therewith, a starting circuit for said finder switches, means under the control of any of said lines in calling for energizing said starting circuit to start a finder switch, a relay for making said lines ineffective to control said starting circuit, 40 and an energizing circuit for said relay completed in the passing engagement of said started finder switch with the terminals of non-calling lines.

12. In a telephone system, the combination 45 with a switch having a plurality of normally inactive brushes and a corresponding plurality of groups of stationary contacts arranged to be traversed by said brushes respectively, of telephone lines arranged in 50 groups terminating in said groups of contacts, a tripping device for each set of brushes for rendering the same active, a group relay for each group of telephone lines operable by the initiation of a call in the 55 corresponding group, an energizing circuit for the corresponding tripping device controlled by each group relay, means controlled by each group relay in its operation for rendering the other group relays inop- 60 erable, means actuated upon the completion of the tripping operation of said switch for rendering the first-operated group relay inoperable and the group relays of the other groups operable by their associated telephone 65 lines, and means actuated by said switch in

completing connection with the calling line for rendering the first-operated group relay operable by its associated lines.

13. In a telephone system, the combination with a line finder having a plurality of normally inactive brushes and a corresponding plurality of groups of stationary contacts arranged to be traversed by said brushes respectively, telephone lines arranged in groups terminating in said groups 70 of contacts, a tripping device for each set of brushes for rendering the same active, a group relay for each group of telephone lines actuated by the initiation of a call in the corresponding group, an energizing circuit 75 for the corresponding tripping device controlled by each group relay, means actuated in the closure of one of said energizing circuits for rendering the other energizing circuits inoperative, and means actuated in the 80 movement of said switch for restoring the operativeness of said energizing circuits.

14. The combination with a finder switch having a plurality of stationary terminals arranged in groups and a multiple-brush 90 movable element with a normally inactive brush for each of said groups of stationary terminals, of a plurality of lines connected with said stationary terminals, an extension circuit connected with said multiple brushes, 95 a tripping device for each of said brushes, said tripping device acting when operated to make the corresponding brush active, electrically-controlled moving mechanism for said movable element, a starting magnet controlling said moving mechanism, a switch associated with each group of lines, means controlled by said switch for operating said starting magnet and tripping device of the 100 associated group, and means controlled jointly by said starting magnet and any line 105 in a particular group for causing the operation of the aforesaid switch of said group.

15. In a telephone system, the combination with a multiple brush line finder, of 110 electromagnetic tripping devices, one for each set of brushes, an energizing circuit having a branch for each of said devices, an electromagnet in the common portion of said energizing circuit, and means controlled by 115 said electromagnet for rendering the other branches inoperative when any one of the branches of said energizing circuit is closed.

16. In a telephone system, the combination with a multiple brush line finder, of 120 electromagnetic tripping devices, one for each set of brushes, an energizing circuit having a branch for each of said devices, closing means for each of said branches, a starting magnet for said line finder in the 125 common portion of said energizing circuit, and means controlled by said starting magnet for rendering the other branches inoperative when any branch of said energizing circuit is closed.

17. The combination with a plurality of telephone lines arranged in groups, of a group relay for each group operated by any line of the corresponding group in calling, 5 group selecting means under the control of said group relays, an energizing circuit having a branch for each of said group relays, and a relay in the common portion of said energizing circuit for preventing the operation 10 of the other group relays when any one of said group relays is operated.
18. In combination, a group of lines, a group of switches, means for operating one of said switches, a starting circuit controlled by any one of said lines for starting the operation of said switch, and means common to the switches of said group for preselecting a plurality of said switches for successive operation. 15
19. In combination, a group of lines, a group of switches, means for operating one of said switches, a starting circuit controlled by any one of said lines for starting the operation of said switch, and an electromagnetic switching device common to the switches of said group for preselecting a plurality of switches of said group for successive operation. 20
20. In combination, a group of lines, a group of switches for making connection therewith, means for preselecting one of said switches for operation, testing means common to the switches of said group for preselecting another of said switches for successive operation, and a starting circuit controlled by any one of said lines for starting the preselected switch operating. 25
21. In combination, a group of lines, a group of switches, means for preselecting one of said switches for operation, means common to the switches of said group and controlled by said preselected switch for allotting another of said switches for a subsequent operation, and a starting circuit controlled by any one of said lines for starting the preselected switch operating. 30
22. In combination, a group of lines, a group of switches, each switch having a definite normal position, means for moving said switches out of their normal position, a starting circuit controlled by any one of said lines for starting the movement of said switches, and means controlled by the movement of a switch out of its normal position 55 for preselecting another of said switches for operation and for selecting a third switch for the successive operation.
23. In combination, a group of lines, a group of switches, each switch having a definite normal position, means for moving a switch out of its normal position, a starting circuit controlled by any one of said lines for starting the operation of said first mentioned means, and means controlled by a switch when moved out of its normal position for preselecting for successive operation a plurality of switches. 60
24. The combination with a plurality of switches, of a starting circuit therefor, one of said switches being normally in operative relation with said starting circuit, means for starting said switch upon the closure of said starting circuit, means individual to each switch for controlling the movement thereof, means actuated by the movement of said switch for operating the controlling means of a second switch from an allotted position to place said second switch in operative relation with said starting circuit, and means actuated by the operation of the controlling means of the second switch for moving the controlling means of a third switch into an allotted position. 70
25. The combination with a plurality of finder switches, of a starting circuit therefor, one of said finder switches being normally in operative relation with said starting circuit, means for starting said finder switch upon the actuation of said starting circuit, means actuated in the starting of said switch for moving a second switch from an allotted position into operative relation with said starting circuit, and means to find an idle switch and move it into the allotted position when said second switch is moved into operative relation with the starting circuit. 80
26. The combination with a starting circuit, of line controlled means for actuating the same, a waiting line finder switch in operative relation with said starting circuit, and means made operative to start said switch when said starting circuit is actuated, on allotted line finder adapted to be moved into waiting position when said waiting line finder started, and means actuated to find an idle line finder and move it into the allotted position when said allotted finder is moved into waiting position. 90

In witness whereof, I hereunto subscribe my name this 29th day of December, A. D. 1916.

ALBEN E. LUNDELL.
